(57) CLAIM

The ornamental design for a handle for a cleaning tool, as shown and described.

DESCRIPTION

FIG. 1 is a top, front, right side isometric view of a handle for a cleaning tool showing our new design;

FIG. 2 is a right side view of the handle for a cleaning tool, the left side view thereof being a mirror image of the right side view;

FIG. 3 is a front view of the handle for a cleaning tool;

FIG. 4 is a rear view of the handle for a cleaning tool;

FIG. 5 is a top view of the handle for a cleaning tool; and,

FIG. 6 is a bottom view of the handle for a cleaning tool.

1 Claim, 3 Drawing Sheets
